UNITED STATES PATENT OFFICE.

GEORGE RICHARDS AND LESLIE NEWMAN BURT, OF LONDON, AND JAMES EDWARD FREEBORN, OF WALTHAMSTOW, ENGLAND.

MILLING SCREW THREADS.

1,427,169.

Specification of Letters Patent. Patented Aug. 29, 1922.

Original application filed April 8, 1920, Serial No. 372,315. Divided and this application filed February 1, 1921. Serial No. 441,666.

To all whom it may concern:

Be it known that we, GEORGE RICHARDS, a citizen of the United States, and LESLIE NEWMAN BURT, a subject of the King of Great Britain and Ireland, both residing at The Outer Temple, 222 Strand, in the city of Westminster, London, England, and JAMES EDWARD FREEBORN, a subject of the King of Great Britain and Ireland, residing at 2 Elmsdale Road, Walthamstow, in the county of Essex, England, have invented new and useful Improvements in Milling Screw Threads, of which the following is a specification.

15 This invention is the subject of a divisional application from Ser. No. 372315, filed 8th April, 1920, and relates to improved apparatus for cutting screw-threads with the aid of what are known as "hobs"; that 20 is to say, rotary cutters wherein the cutting teeth follow spiral lines having a pitch corresponding with that of the thread to be formed.

It has hitherto been the practice to impart 25 to the hob and to the work-piece the same rotative speed, but neither partakes of any axial movement. Under such conditions, it is necessary to make special provision for the elimination of facets, which result from 30 the cutting teeth coming successively into operation upon the work at the same points in successive revolutions. There is, moreover, the objection that the portion of the work-piece threaded is restricted in length 35 to that of the hob. A further objection is that, when using a multiple-thread hob, difficulties occur in shaping the toothed thread on the hob, in such a manner as to cut, in the work, a thread of the correct shape.

40 With a view to avoiding these objections, we mount the hob-spindle in a frame capable of being canted; such frame being mounted on a slide, so as to admit of the hob being advanced laterally towards the work-piece 45 with a view to cutting the thread in the latter to the required depth. The said slide is in turn mounted on a saddle, adapted to be traversed upon the bed of the machine, and is provided with a screw of predetermined pitch for effecting such movement. When 50 the hob-spindle is tilted in a vertical plane, and when extreme accuracy is required in the form of the thread cut, the surface of

the hob is made slightly curved in a longitudinal direction, or, for internal work, 55 slightly barrel-shaped.

The work-spindle, which is mounted in the headstock of the machine, is in gear with the hob-spindle; these two spindles revolving, contrary to the usual practice at slightly different speeds. The work spindle is also in gear with the screw which operates the traverse slide, the pitch of the said screw, or the gearing whereby it is driven, being proportioned to the difference between the 60 rotative speed of the work-spindle and that of the hob-spindle.

Under such conditions, by reason of the axial advance of the hob in relation to the work, the rotative speed of the former, or 70 of the latter, being varied to suit, we are able to screw-thread portions of the work the length of which considerably exceeds that of the hob. Moreover, as work-threads 75 are cut by the leading hob-threads, are subsequently operated on by the following hob-threads, any facets formed by the leading hob-threads become eliminated.

The provision of substantial and rigid support for the cutter-spindle is of importance, and is facilitated by the employment 80 of a taper hob.

Apparatus adapted for use in carrying our invention into effect is illustrated in the accompanying drawings, whereof Fig. 1 is a vertical section of part of the gear employed to drive the cutter spindle, Fig. 2 being a partly diagrammatic end elevation illustrating gears arranged between the latter and a traversing shaft hereinafter referred 85 to. Fig. 3 is a part plan illustrating certain further details of the traversing mechanism, whilst Figs. 4 and 5 are part views in plan illustrating the application of our invention where a taper hob is employed. Figs. 6 and 95 7 are respectively a sectional plan and a front elevation showing the general arrangement of the apparatus, whilst Fig. 8 is a diagrammatic view illustrating certain further gearing hereinafter described.

100 By transmitting to the cutter-spindle, by way of a suitably arranged differential gear, the rotative movement which is imparted to the carriage traversing mechanism, the hob may be speeded up, or retarded, according 105 to the direction of travel, in such a manner

that the relation between the hob-threads and the threads on the work remains undisturbed when the hob is moved longitudinally; thus enabling the work-piece to be 5 screw-threaded over a length greatly exceeding that of the hob.

As shown in Fig. 1, the drive is transmitted from the back-shaft a to a worm-wheel a^1 mounted on a bearing attached to 10 a saddle b . In a suitable bracket b^1 mounted upon the worm-wheel a^1 and able to revolve with the latter, is arranged a short shaft c whereon are freely mounted two similar bevel-wheels c^1, c^2 , which mesh with a bevel-wheel d , mounted on a shaft d^1 , whereof the 15 outer extremity carries a spur-wheel d^2 .

The bevel-wheels c^1, c^2 , also mesh with a further bevel-wheel e , mounted upon a cross-shaft f , from which the cutter-spindle is 20 driven. From the back-shaft a driving the worm-wheel a^1 , the drive is transmitted to the cross-shaft f , by way of the bevel-wheels c^1, c^2 , meshing with the bevel-wheel d , and thence to the bevel-wheel e , which is fast 25 upon the cross-shaft f ; the bevel-wheel d remaining locked when, as in cutting a short length of screw-thread, no traverse of the hob is effected.

The traverse of the saddle b , and hence 30 that of the hob, is effected by transmitting the power supplied by the back-shaft a through suitable gears g, g^1, g^2 , as shown in Fig. 2, to drive the worm-shaft h at a suitable speed; provision being made for 35 throwing these gears into and out of engagement. The worm-shaft h carries a worm h^1 which meshes with a worm-wheel h^2 , the boss of which is internally screw-threaded to form a nut adapted to traverse 40 the lead-screw j which is held against rotation. The outer extremity of the worm-shaft h carries a spur-wheel h^3 , which, as shown in Fig. 3, meshes with the spur-wheel d^2 , through one or more suitable idlers, such 45 as d^3 ; provision being, moreover, made for varying the said spur-wheels and idlers in order to establish different speed ratios adapted to produce threads of the particular form required.

50 Short lengths of thread, less than or equal to the hob in length may thus be cut without any endwise motion of the saddle b when the feed-drive is, by any suitable means, thrown out of engagement; but 55 should a "creep" motion be required in these short lengths of thread, a hand-lever may be attached to the front end of the worm-shaft h , and the required "creep" be produced by hand, as described and illustrated in the 60 specification to the co-pending application of George Richards, filed 5th February, 1917, Ser. No. 146692.

As an alternative, the lead-screw may be driven in conjunction with similar gear to 65 produce the same effect; or the lead-screw

may be driven direct, producing a different speed ratio from that of the hob, as in Fig. 5.

In order to permit of the cutter-spindle being rigidly supported, a taper hob may be 70 employed, so as to permit of the carriage assuming an angular position in relation to the work; thus providing the necessary clearance for a substantial and steady carriage, as shown in Figs. 4 and 5. 75

To enable the hob to assume the correct position for the teeth to cut in the path of the helix angle of the thread on the work, the saddle b is, as shown in Fig. 6, mounted on a bed k and carries a cross-slide l which 80 may be moved laterally to obtain various depths of thread by means of a screw-spindle m .

The cross-slide b carries a pivotally mounted carriage n , arranged vertically in 85 relation to the bed k , and adapted to rotate about the centre k^1 , as shown diagrammatically in Fig. 8, in order to adjust the axis of the hob to any angle required.

The carriage n which supports the cutter-spindle p may, by means of the screw o and hand-wheel o^1 , be adjusted vertically on slides carried by the pivotally mounted carriage n , as illustrated in Fig. 7. The drive for the cutter-spindle p is imparted, as 95 shown in Fig. 6, from the cross-shaft f through suitable spur-wheels p^1, p^2, p^3, p^4 , whereof the last indicated is free to revolve about the centre k^1 whereon the spur-wheel p^3 is mounted. 100

The spur-wheels p^1, p^2, p^3 , are mounted in the cross-slide l ; the spur-wheel p^1 being free to slide upon a spline along the cross-shaft f .

The spur-wheel p^4 drives the worm-shaft 105 r shown in Fig. 6, and thence, by way of the worm r^1 , and the worm-wheel s^1 , the vertical shaft s upon which the worm-wheel t is free to slide vertically upon a spline, as shown in Fig. 7; the cutter-spindle p being 110 driven by means of a worm-wheel x mounted at its extremity and meshing with the worm-wheel t .

Under such conditions, the hob-teeth may be adjusted to cut along any angle required 115 to conform with the helix of any particular thread. Furthermore, on reaching the end of the thread, when using a parallel hob, the carriage n may be fed downwards to finish those threads, which, by reason of the 120 end of the hob being canted above the work-centre, have been left unfinished.

We claim:

1. In a screw-thread milling machine wherein a cutter of the "hob" type is employed, the combination, with a transverse slide, of a carriage rotatably mounted upon the latter, and a cutter-spindle supported from the carriage and adjustable as regards its height and inclination. 125

2. In a screw-thread milling machine wherein a cutter of the "hob" type is employed, the combination, with a cutter-spindle and its carriage, of a worm-shaft, carrying a spur-wheel meshing with and revolute about a spur-wheel mounted upon the centre about which the cutter-spindle-carriage is rotatable.
3. In a screw-thread milling machine
- wherein a cutter of the "hob" type is employed, the combination, with a saddle-traversing worm-shaft, of a cutter-spindle driving shaft, the two shafts being coupled together by way of a differential speed-gear. 10
